UNITED STATES PATENT OFFICE.

HENRY KREISINGER, OF PIERMONT, NEW YORK, ASSIGNOR TO COMBUSTION ENGINEERING CORPORATION, OF NEW YORK, N. Y., A CORPORATION OF NEW YORK.

BURNING OF FUEL.

Application filed October 11, 1924. Serial No. 742,976.

My invention relates to the burning of fuel on grates and in suspension, and especially to the burning of fuel in both ways concurrently. In doing this, I aim to obviate or remedy various drawbacks of either method alone: e. g., to avoid all difficulty from slagging in the case of powdered fuel, for example, to reduce the percentage of uncombined oxygen in the products of combustion from the fuel on the grate; and to improve the efficiency of combustion over what is ordinarily attained by either method alone. My invention is especially advantageous in the burning of relatively coarsely pulverized grate fuels, such as No. 4 buckwheat, culm or slush for example. It is conveniently applicable in connection with automatic stokers; and I have hereinafter explained it with special reference to such a mode of use.

In the drawing, Fig. 1 shows a vertical section through a steam boiler powdered fuel furnace, equipped with a Coxe stoker.

Fig. 2 shows a cross-section through one of the travelling grate members, on a larger scale than Fig. 1.

In Fig. 1 is shown a water tube boiler of familiar type, comprising a transverse drum 10 connected to approximately upright front and rear headers 11, 12. These headers 11, 12 are themselves interconnected by banks of "fore and aft" water tubes 13, inclined upward toward the rear,—speaking of front and rear in reference to the regions where the powdered fuel nozzles are located and whence the products of combustion make exit from its main combustion space or chamber 15, respectively. The water tubes 13 overlie an opening in the top or roof 16 of the combustion chamber 15, and the furnace gases take a circuitous course among them (as partly defined by the baffling 17, 18, 19) on their way to the stack.

As shown in Fig. 1, the combustion chamber proper at 15 is a large, deep, unobstructed chamber enclosed by walls which slope outward slightly, so that the chamber as a whole expands upwardly. Powdered fuel preferably with somewhat more than carrying air is fed in through one or more downwardly directed burners 25 mounted in the roof 16 near the front wall 26, and is continually ignited by the heat of the latter and of the furnace. Air additional to that entering at the burner 25 is (or may be) supplied through damper controlled inlet-openings 27 at various heights

in the front wall 26. The burning stream (of mingled air, powdered fuel, combustible gases from the fuel, and products of combustion) descends in the front of the chamber 15 until its momentum is overcome by the upward draft through the boiler. It then bends rearward and ascends, and finally passes from the combustion chamber to the rear (upper) pass of the boiler as already described,—all about as indicated by the arrows. The size of the chamber 15 and the contiguity of the unbaffled downward and upward fuel streams and their change of direction as described assure rapid and complete combustion in the chamber 15.

At the bottom of the chamber 15, fuel, such as mentioned above, is burned by means of any suitable grate or stoker, here shown as a travelling grate stoker 30 of the Coxe type. The active upper run of the stoker 30 travels from the rear toward the front, and the fuel is supplied thereto at the rear, as diagrammatically indicated at 31. On its way from the rear to the front, the fuel passes through the various stages of combustion in succession and is completely burned. The final residue of ash passes under the water back 32 at the bottom of the front wall 26 and is discharged (as shown) as the grate 30 makes its front turn at 33. Air for combustion of the fuel is supplied through the grate 30. For this purpose, a sheet metal casing 34 with a plurality of pressure compartments 35, 36, 37, 38 is arranged between the upper and lower runs of the grate 30. The fuel supporting metal bars or "keys" 39 of the stoker 30 have a multiplicity of air holes or jet openings 41 through them, and the tops of the chambers 35, 36, 37, 38 are open, so that the air from these chambers is discharged through the holes in a multiplicity of jets. Preferably, the holes 41 slope upward to the rear, as shown, so that the air jets from them are correspondingly directed. The air thus supplied not only maintains combustion of the fuel on the grate 30, but also cools the grate and protects it from burning out. The air pressure in the several chambers 35, 36, 37, 38 is regulated according to the requirements of the fuel in its various stages of combustion from the rear to the front of the furnace.

Preferably, the total amount of air supplied through the grate 30 is somewhat in excess of that required for complete combustion of the fuel thereon, so that the surplus

may assist in the combustion of the superjacent pulverized fuel stream. As the pulverized fuel stream passes rearward across the fuel bed on the grate 30, the rearward-inclined air and flame jets from the fuel bed strike it convergently, and are deflected rearward by it. As a result, a series of eddies is set up along the lower edge of the pulverized fuel stream, thus assuring thorough intermixture of the air with the fuel and burning gases, and promoting complete combustion.

Besides the inter-action between the fuel bed on the grate 30 and the pulverized fuel stream as regards combustion, important advantage is secured in respect of the incombustible residue or ash from the pulverized fuel. This relatively heavy residue continually falls upon the fuel bed on the travelling grate 30, and is continually carried along and discharged by the grate with the ash from the combustion of the fuel burned thereon. Toward the front of the furnace, where combustion on the grate 30 has been completed, the jets of air passing through the grate cool the ash from both sources below slagging temperature, and prevent it from running together into a solid mass. This obviates all necessity for maintaining a cooling zone in the lower region of the combustion chamber 15,—whether by a water screen, or by admission of air in excess of that required for complete combustion, or by any other means,—so that the percentage of air in the stack gases is less, and the temperature of the products of combustion as they enter the boiler is greater.

By the invention, small sizes of coal may be fed with the pulverized coal so that a large proportion of the fuel may be fed to the burners. Also of coals having low ash and high ash content, only the low ash grade coal need be pulverized, the other being burnt on the grate.

I claim:

1. The method of burning fuel on a travelling grate and pulverized fuel in suspension in a common combustion chamber with exit

for products of combustion from its upper rear region, which method comprises directing a powdered fuel stream downward in 50 the front of the combustion chamber, and blowing air upward through the moving fuel bed in rearward-inclined jets.

2. A combined lump and powdered fuel burning furnace comprising a travelling grate and a combustion chamber thereover with exit for products of combustion at the rear and means for introducing a downward directed fuel stream into the front thereof, and means for blowing air upward through 60 the fuel bed in rearward-inclined jets.

3. A combined lump fuel and powdered fuel burning furnace comprising a travelling grate adapted to receive fuel at the rear and progress it forward as it burns, and a combustion chamber thereover with exit for products of combustion at the rear and means for introducing a downward directed fuel stream into the front thereof, and means for blowing air upward through the fuel bed in rearward-inclined jets. 70

4. The method of burning powdered and coarse fuel in a common combustion chamber, which comprises moving a bed of coarse fuel forwardly in the chamber, directing a stream 75 of powdered fuel over said fuel bed in a general rearward direction, blowing air through the bed in a rearward direction, and drawing off the products of combustion at the rear.

5. The method of burning coarse fuel on 80 a grate and powdered fuel in a common combustion chamber with exit for products of combustion in its upper region, which method comprises moving the bed of fuel in one direction in the chamber, directing a powdered fuel stream downward in the combustion chamber and in a direction opposite the movement of the fuel bed, and causing said stream to bend upward over the fuel bed and rise with the products of combustion therefrom. 85 90

In testimony whereof, I have hereunto signed my name.

HENRY KREISINGER.
